UNITED STATES PATENT OFFICE.

AARON B. HARTMAN, OF ONAWA, IOWA, ASSIGNOR TO HIMSELF AND
J. M. JIVIDEN, OF SAME PLACE.

FENCE-POST.

SPECIFICATION forming part of Letters Patent No. 224,902, dated February 24, 1880.

Application filed December 1, 1879.

To all whom it may concern:

Be it known that I, AARON B. HARTMAN, of Onawa, in the county of Monona and State of Iowa, have invented a new and useful Improvement in Fence-Posts, of which the following is a specification.

The object of my invention is to construct a durable fence-post by simple and convenient means and of materials available in most places.

For attaching wooden rails a bar of wood is combined with the iron rods, and for wire fences the wires are connected by staples. This fence-post is made at the place where set by filling a hole in the ground with a composition for the base and inserting the rods; or stone may be drilled with holes to receive the rods.

My improved fence-post is shown in the accompanying drawings, wherein Figure 1 is a front elevation. Fig. 2 is a vertical section on line *x x* of Fig. 1.

Similar letters of reference indicate corresponding parts.

A is the stone base. *a a a* are the vertical rods or tubes of the post, secured in base *A* and united together at the top. *b* is a bar of wood fitted between the rods *a*, to which the rails *c* of the fence are secured, and *d d* represent wires secured to rods *a* by staples *e*.

The base *A* may be of stone, drilled to receive the lower end of rods *a*, which will then be secured by cement; or the base *A* may be artificial stone formed by filling the previously-prepared hole with suitable composition and inserting the rods before the material sets. I prefer a composition of Portland cement and gravel, with linseed-oil to toughen the stone and neutralize the alkali that may be in the gravel.

The rods or tubes *a* will be about one-half inch in diameter, formed with short bends at their lower ends. These rods are welded to-

gether at the top, and the lower ends spread apart a sufficient distance to give a brace to the rods, the front rods being placed on the fence-line. These front rods are slotted to receive the staples *e* that secure the wires *d* of a wire fence.

The vertical wooden bar *b* is of a size and form to enter between the rods, sufficient space being left for circulation of air; and to this bar *b* the rails *c* are attached by nails, screws, or other suitable means, so that the rails *c* and bar *b* will be sustained by rods *a*.

For a picket-fence screw-bolts may be used for sustaining the horizontal rails, the bolts having a hook to pass around the rear rod, *a*.

In the construction of a fence with these posts the composition may be mixed in a box-wagon and the wagon drawn along the line of fence from one post-hole to another as the posts are completed. The work may thus be done rapidly and in a durable and substantial manner, the posts being set up with but little labor.

The materials used are such as may be obtained in nearly every section of the country, and require no transportation of waste material.

When once set the wooden portions of the fence may be readily and cheaply renewed, as required.

Having thus fully described my invention, I claim as new and desire to secure by Letters Patent—

The combination of the rods *a*, fixed in base *A*, and provided with staples *e*, the wooden post *b*, the wire rails *d*, and the wooden rails *c*, the latter nailed or screwed to the post *b*, as shown and described.

AARON B. HARTMAN.
